UNITED STATES PATENT OFFICE.

WILLIAM FISCHER, OF NEW YORK, N. Y.

DESIGN FOR A GEM-SETTING.

55,260.

Specification for Design.

Patented May 25, 1920.

Application filed December 29, 1919. Serial No. 348,191. Term of patent 3½ years.

To all whom it may concern:

Be it known that I, WILLIAM FISCHER, a citizen of the United States, and a resident of the city of New York, borough of Manhattan, in the county and State of New York, have invented a new, original, and ornamental Design for a Gem-Setting, of which the following is a specification, reference being had to the accompanying drawings, forming a part thereof.

Figure 1 is a plan view of a gem setting showing my new design; and

Fig. 2 is a side elevation of the same as applied to a ring shown in broken lines.

I claim:

The ornamental design for a gem setting as shown.

WILLIAM FISCHER.
